BOAT ANCHOR

James F. Hottel, Washington, D. C.

Application December 24, 1938, Serial No. 247,692

9 Claims. (Cl. 114—208)

(Granted under the act of March 3, 1883, as
amended April 30, 1928; 370 O. G. 757)

The invention described herein may be manufactured and used by or for the Government of the United States for governmental purposes without payment to me of any royalty thereon in accordance with the provisions of the act of April 30, 1928 (Ch. 406, 45 Stat. L. 467).

This invention pertains to boat anchors. Objects of the invention are to provide a non-fouling, light-weight, simple, practicable and efficient, as well as economical boat anchor incorporating features whereby its compactness for stowing purposes make the same of particular desirability.

Other objects of the invention will be pointed out and become apparent in the following specification and accompanying drawing illustrating a practical embodiment of the invention and by which the same may be practiced.

Fig. 1 of the drawing illustrates a perspective of an embodiment in an open and operable position, 20 while the elevational view in

Fig. 2 illustrates the same in closed position most suitable for stowage.

Broadly, my invention comprises an anchor, the shank of which consists of a pair of angular related beams positioned substantially in a common plane and arms extending therefrom adapted to support earth engaging flukes. The fluke-carrying arms extend in substantially opposite directions from the beams, and are disposed in angular relation to the common plane of the beams.

In the embodiment of the invention illustrated the shank of the anchor comprises a pair of beams 10 and 11. These beams are coupled together at one end in a manner whereby the angular relation of one with respect to the other may be varied. To provide this adjustability the beams may be hingedly coupled or coupled, as shown, by a swivel bolt or pin 12, which pin may also serve as a suitable means for the attachment of a clevis or ring to which the anchor rope may be secured.

In the embodiment shown, the shank beams 10 and 11 are cross sectionally T-shaped and in the use of T-beams a number of advantages and desirable features are provided. Such beams possess a maximum or at least an adequate strength for the purpose, since the legs 14 and 15 of the T's serve as reinforcements. Furthermore, beams of this design may be conventionally swiveled back to back, or in other words, with the head portions 16 and 17 of the beams face to face, whereby in the angular adjustment of the beams the same act in a scissor-like manner. By this arrangement the overlapping flat surfaces of the

head portions 16 and 17 of the beams support each other against torsional strain and displacement. Portions of the legs 14 and 15 may be cut away as at 18 on the swiveled ends of the beams in order that a hole for the swivel pin 12 may be disposed centrally through the head portions 16 and 17 of the beams, or on the axis of the legs 14 and 15. Portions of the heads 16 and 17 may be cut away on the ends opposite their swiveled ends to provide shoulders 20 and 21 inwardly of the projecting ends 22 and 23 of the leg portions 14 and 15 for purposes to be described hereinafter.

Means are provided to fix the beams 10 and 11 in closed juxtaposition and opened at predetermined angles with respect to each other. These relative positions may be suitably maintained by the provision of ear-like members 24—25 and 26—27, projecting reversely from the respective edges of the head portions 16 and 17 of the beams 10 and 11, which ears are provided with means for cooperatively securing the overlapping ears of the respective pairs in fixed predetermined positions. For this purpose one or more holes 28 are provided in the ears 24—25 and 26—27 suitable to receive bolts or pins 29. These holes 28 are arranged in a manner whereby those through the ears 25—26 will coincide or register with each other when the beams are spread in the direction shown in Fig. 1. Likewise the holes 30 through the ears 24 and 27 are arranged to register with each other should the beams be spread in the opposite direction. The holes 28 are also arranged in a manner whereby those through the ears 24 and 25 will register with those through the ears 26 and 27 when the beams are in closed position as shown in Fig. 2.

The flukes 30 and 31 of the anchor are carried on arms 32 and 33, which arms are hingedly or pivotally connected to the free ends of the beams 10 and 11 in a manner whereby they may be moved to predetermined opened positions in a direction angularly with respect to the plane through which the shank beams 10 and 11 may be moved.

The fluke arms may consist of square bar material, or any other suitable bars, worked and bent to shape, preferably with an elbow intermediate the ends to properly position the flukes. The top of the flukes may be, as shown, crowned to prevent fouling and are preferably shovel shaped or concave to increase their holding effects. They may also be sharpened and formed with a pointed pea to increase their digging effects. These flukes are welded or otherwise

secured to one end of the fluke arms with their peas foremost. The fluke arms may be connected to the free ends of the shank beams in any suitable manner which will afford angular adjustments of the arms with respect to the shank beams in a direction substantially normal to the plain through which the shank beams are angularly adjustable. A strength giving and strain relieving manner of adjustably connecting the arms to the shank beams is illustrated in the drawing wherein it will be seen that the ends of the fluke arms are slotted or bifurcated and straddle the end portions 22 and 23 of the legs 14 and 15 of the shank beams. Holes are provided in the forked portions of the fluke arms and in the projecting leg portions 22 and 23 whereby bolts, pins or pivots 34 and 35 may be passed therethrough to hingedly connect the arms to the beams. The holes through the forked portions of the fluke arms and the projections 22 and 23 should be so arranged as to allow the ends of the forked portions to abut the shoulders 20 and 21, formed by the cut back ends of the head portions 16 and 17 of the shank beams, serving as means for bracing the arms when in fully open position and also for limiting the opening of the arms beyond a most effective angle for the flukes.

To maintain the flukes in predetermined angular positions with respect to the shank beams, arm or lip portions 36 and 37, which may also be referred to as quadrant plates, may also be provided extending from the leg portions 14 and 15 of the beams through the fork provided in the ends of the fluke arms 32 and 33 and having stops 38 and 39 which prevent the fluke arms from being opened beyond a predetermined position. To retain the arms 32 and 33 either in open position in abutment with the stops 38 and 39, or in closed position whereby the peas of the flukes rest against the leg portions 14 and 15 of the beams, the members 36 and 37 are provided with a series of openings through which pins or bolts 40 and 41 may be passed.

The members 36 and 37 assist to relieve the fluke arms and the pins 34 and 35 of the torsional strain by being passed through the crotch of the forked portions of the fluke arms.

In the construction of smaller anchors either the members 36 and 37 or the abutting features of the shoulders 20 and 21 may be omitted. Again in the smaller type of anchors it is within the scope of my invention to omit both of the features just described for preventing the fluke arms from opening beyond predetermined angles with respect to the shank beams and utilize any suitable tying or bracing members capable of sustaining the tension or compression tending to vary predetermined angles between the fluke arms and the shank beams. Such tying or bracing members may also be substituted for the ear-like members 24-25 and 26-27 in the smaller type of anchors.

By this arrangement it will be seen that I provide an anchor which, when folded as shown in Fig. 2, is free of all projecting arms, prongs, etc., invariably causing entanglements with anchor ropes and provide an anchor which may be folded into a compact unit requiring very little storage space as compared with conventional anchors which are fixed in open position.

In preparing the closed anchor, as shown in Fig. 2, for launching, the pins or bolts 40 and 41 are withdrawn from behind the fluke arms, the arms opened into abutment with the stops, and the pins 40 and 41 reinserted in front of the

fluke arms to hold them open and in abutment with the stops. The pins 29 holding the shank arms in juxtaposition are then removed, the shank arms spread to predetermined positions, and the pins 29 passed through any coinciding holes 28 through the overlapping ears.

From the foregoing it will be seen that I provide an anchor with maximum holding properties and so designed as to normally fall clear with one of the fluke arms in position to dig in irrespective of which way the anchor may fall. The design of the anchor is also such that should the line foul in letting go the first strain will capsize and clear the anchor, bringing it into proper position. If the anchor lands as shown in Fig. 1 the fluke 31 is automatically in position for engagement with the earth and if the anchor should land in the reverse position the fluke 30 would be in the position in which the fluke 31 is now shown. Again, if the anchor should land with the fluke arm 32 horizontally with respect to the surface of the earth the overbalancing weight of the angularly disposed other arm 33 will cause the anchor to topple over into a position such as is shown in Fig. 1 whereby it will immediately dig in by its falling force, by its own weight or upon the least towing.

I claim:

1. A foldable anchor comprising a pair of beams swiveled shearingly adjustable one past 30 the other from superimposed parallel positions to predetermined angles, means for releasably maintaining said beams at any one of a plurality of angles with respect to each other, arm-like members swivelly mounted one to each beam, means 35 for releasably maintaining predetermined angles between said arm-like members and the respective beams, and flukes fixed to the respective arm-like members.

2. A foldable anchor comprising a pair of 40 beams swiveled scissor like in an overlapping manner to relieve each other of torsional strain, means for releasably maintaining predetermined angles between said beams, a pair of fluke-provided arms swiveled respectively one to each free 45 end of said beams, and means for releasably maintaining predetermined angles between said arms and the respective beams.

3. A foldable anchor comprising scissorbeams each having a single fluke hinged to the free ends 50 thereof, means for releasably maintaining said beams at predetermined angles to each other, and means for releasably maintaining said flukes at predetermined opposing angles to the beams to which they are respectively hinged.

4. A collapsible anchor comprising a plurality of superimposedly overlapping beams coupled together at one end in a manner whereby the angle between the beams may be varied while maintaining at least a partial overlapping relation 60 tending to relieve said beams of torsional strain, means for releasably maintaining predetermined angular positions of the beams with respect to each other, flukes coupled to the free ends of said beams in a manner whereby the angle between 65 the flukes and their respective beams may be varied, and means for releasably maintaining predetermined angular positions of the flukes with respect to their respective beams.

5. A collapsible anchor comprising a pair of 70 T-beams coupled together face to face at one end thereof in a manner whereby the angle between the beams may be varied, earlike members projecting from the edges of said beams, means for releasably securing an ear-like member of one 75

beam to an ear-like member of the other beam for releasably maintaining predetermined positions of one beam with respect to the other, a pair of fluke-provided arms each having a bifurcated end to receive a leg of one of said T-beams, means coupling said arms to said T-beams in a manner whereby the angle between said arms and beams may be varied, tongue-like members projecting from the legs of said T-beams and passing through said arms, and means associated with said tongue-like members for releasably maintaining predetermined angular positions of said arms with respect to said beams.

6. A collapsible anchor comprising a plurality of beams coupled together at one end in a manner whereby the angle between the beams may be varied, said beams having a reinforcing flange disposed longitudinally along one face thereof, ear-like members projecting from the edges of said beams, means for releasably securing an ear-like member of one beam to an ear-like member of another beam for releasably maintaining predetermined angularities of one beam with respect to another, arm-like members each having a bifurcated end portion to receive one of said reinforcing flanges, means hingedly connecting said bifurcated arm portions to said beam reinforcing flanges, tongue-like members projecting from said flanges through the bifurcated portions of said arms, means associated with said tongue-like members for releasably maintaining angular positions of said arms with respect to

said beams, and flukes secured to said arm-like members.

7. An anchor comprising a pair of beams swiveled face to face and separable at one end substantially in a common plane to regularly related positions, arms adapted to support earth engaging flukes hingedly attached to the separable ends of said beams, said arms extending one from each of said beams in substantially opposite directions, and means releasably maintaining said arms, disposed in angular relation to said common plane.

8. An anchor comprising a pair of swiveled beams angularly separable at one end substantially in a common plane, arms adapted to support earth engaging flukes, secured hingedly one to each of said beams, means for releasably maintaining said arms in extended positions substantially opposite from said beams and in angular relation to said common plane, and means tending to relieve the fluke arms of torsional stresses and displacement.

9. An anchor comprising a pair of beams disposed in adjustable angular relation, said beams having overlapping contacting portions tending to relieve each other of torsional strain, earth engaging means, said means comprising arms having flukes carried thereby, the arms being disposed in adjustable angular relation with respect to and carried by said beams, and means for limiting the angular relation between said arms and beams.

JAMES F. HOTTEL.

CERTIFICATE OF CORRECTION.

Patent No. 2,202,856.

June 4, 1940.

JAMES F. HOTTEL.

It is hereby certified that error appears in the printed specification of the above numbered patent requiring correction as follows: Page 1, first column, line 6, for "Ch. 406" read --Ch. 460--; page 3, second column, line 5, claim 7, for the word "regularly" read --angularly--; and that the said Letters Patent should be read with this correction therein that the same may conform to the record of the case in the Patent Office.

Signed and sealed this 9th day of July, A. D. 1940.
